US0D1019710S

(12) **United States Design Patent** (10) **Patent No.:** **US D1,019,710 S**
(45) **Date of Patent:** **** Mar. 26, 2024**

(54) **ROOT PULLER**

(71) Applicant: **YONGKANG MAXPOWER TECHNOLOGY CO., LTD.**,
Yongkang (CN)

(72) Inventor: **Xuancong Jin**, Yongkang (CN)

(73) Assignee: **YONGKANG MAXPOWER TECHNOLOGY CO., LTD.**,
Yongkang (CN)

(**) Term: **15 Years**

(21) Appl. No.: **29/857,712**

(22) Filed: **Oct. 25, 2022**

(30) **Foreign Application Priority Data**

Oct. 14, 2022 (CN) 202230678049.8

(51) **LOC (14) Cl.** **12-09**

(52) **U.S. Cl.**

USPC **D15/23; D15/24**

(58) **Field of Classification Search**

(57) **CLAIM**

The ornamental design for a root puller, as shown and described.

DESCRIPTION

FIG. 1 is the first perspective view of a root puller showing the new design;

FIG. 2 is the second perspective view thereof;

FIG. 3 is the third perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken line showing of the circular elements in FIG. 9 is included for the purpose of illustrating portions of the root puller and forms no part of the claimed design.

1 Claim, 9 Drawing Sheets
